UNITED STATES PATENT OFFICE.

WILFRED S. YOUNG, OF CHICAGO, ILLINOIS, ASSIGNOR TO ECONOMY ENGINEERING COMPANY, OF CHICAGO, ILLINOIS, A CORPORATION OF ILLINOIS.

PORTABLE ELEVATING APPARATUS.

Application filed June 30, 1921. Serial No. 481,564.

To all whom it may concern:

Be it known that I, WILFRED S. YOUNG, a citizen of the United States, residing at Chicago, in the county of Cook and State of Illinois, have invented certain new and useful Improvements in Portable Elevating Apparatus, of which the following is a specification.

The invention relates to machines of the type generally known as tiering machines, which are adapted for use in warehouses and similar places for raising and lowering bundles, bales, boxes and the like in the operation of stacking the same in tiers for the purposes of storage, and unstacking them upon removal from the warehouses.

The aim of the invention is to provide an apparatus of the character described which is very simple in construction and adapted for convenient and efficient operation.

One object of the invention is to provide a tiering machine which is capable of operation either by motive power or hand power as may be desired.

Another object of the invention is to provide a machine which is operable manually or by motive power and in which a single brake mechanism is capable of sustaining the load at the desired elevation.

A further object of the invention is to provide a brake mechanism of the character set forth which is of an extremely simple construction and automatic in operation.

Other objects and advantages will be apparent as the description proceeds, reference being made to the accompanying drawings wherein I have illustrated a preferred embodiment of the invention. It is to be understood, however, that while only one embodiment is illustrated, the invention is not to be limited in the interpretation of the appended claims to any particular form, construction and arrangement except as may be necessitated by the state of the prior art.

In the drawings, Figure 1 is a fragmentary side elevation of a tiering machine embodying my invention. Fig. 2 is a detail view on an enlarged scale illustrating a portion of the brake mechanism. Fig. 3 is a plan view on an enlarged scale, of the operating mechanism, the upper portion of the frame being shown in section. Fig. 4 is a fragmentary vertical sectional view on an enlarged scale taken substantially in the plane of line 4-4 of Fig. 3. Figs. 5 and 6

are sectional views taken on an enlarged scale substantially in the plane of line 5-6 of Fig. 3, and illustrating the parts in different operative positions. Fig. 7 is a perspective view illustrating one of the cams 60 employed in the brake mechanism.

Referring to Figs. 1 and 3, the machine comprises generally a base frame 8 mounted upon rear wheels 9 and a forward leg 10. A forward caster wheel 11 is rigid with a draw bar or handle 12 and is adapted upon operation to raise the frame so as to carry the leg 10 from off the floor. An upright frame 13 is carried by the base frame 8 and this frame constitutes a guide for a platform 14 which is connected by means of a cable 15 with a winding drum 16. The latter is suitably journaled in the framework 17 of the machine of which the base frame 8 and the upright frame 13 forms a part, the drum 70 being provided with a suitable shaft 18 for this purpose. An electric motor 19 or other suitable source of motive power is supported upon the base frame 8 and is operatively connected with the drum 16 so as to be capable of winding the cable 15 in the operation of raising and lowering the platform.

The means for thus operatively connecting the motor 19 with the drum 16 comprises a main shaft 20 driven from a counter shaft 21 which, in turn is driven from the motor. To this end, the motor shaft is provided with a sprocket wheel 22 connected by means of a chain 23 with a sprocket 24 fixed upon the countershaft. A second sprocket 90 25 on the countershaft is connected by means of chain 26 with a sprocket 27 upon the main or driven shaft. The main shaft 20 has keyed thereon a pinion 28 which meshes with a spur gear 29 fixed upon the drum 95 shaft 18. Thus when the shaft 20 is actuated rotation is imparted to the winding drum 16. It will be understood that the driving connections thus described are suitably proportioned to give the desired speed 100 to the drum.

The shaft 20 is also adapted to be driven manually as by means of a crank 30, and the arrangement is such that the shaft may be rotated either manually or by motive 105 power as may be desired, the two driving means being independent of each other. Referring to Figs. 5 and 6, 31 designates a brake drum which is rotatably mounted upon the shaft 20 and normally engaged 110

by a brake band 32 (Fig. 2) which is manually operable by means of a hand lever 33 (Fig. 1) mounted on a bracket 32^a and operable to release the brake drum for rotation. Herein the brake band 32 is shown as constructed in two sections pivoted at their lower ends as at 34 and connected at their upper ends by means of a rod 35 carrying a pair of nuts 36 on its opposite ends and 5 a pair of springs 37 interposed between the respective nuts and sections of the band whereby normally to cause the band to engage the drum. A toggle linkage 38 is interposed between the upper ends of the 10 sections of the band, and an operating rod 39 connected with said linkage is arranged to be operated by means of the lever 33 through suitable connections comprising a lever 40 and a link 41, the lever 33 being 15 formed at its lower end to provide a bell crank with which the link 41 is connected. The lever 40 is fulcrumed upon a bracket 42 suitably mounted upon the framework of the machine, and it will be seen that the 20 link 41 and the lower end of the lever 33 constitute a toggle such that the brake band may be operated with substantial ease to 25 release it from the drum 31.

Operatively associated with the drum 31 30 is a pair of brake members 43 and 44, and means is provided whereby when the shaft is rotated either by motive power transmitted to the sprocket 27, or by hand power applied through the medium of the crank 30, 35 said brake members release the drum for operation with the shaft independently of the drum. This means comprises a sleeve 45 keyed upon the inner end of the shaft 20 and held against endwise movement thereon by means of a nut 46. Said sleeve 45 at its forward end is provided with a cam disk 47 herein formed integral with the sleeve. The brake member 44 has 40 formed rigid therewith a cam sleeve 48 and said disk and sleeve are provided with complementary cam faces 49 such that when the shaft 20 is rotated in a direction to raise the load, the cam disk 47 moves with reference to the cam sleeve 48 so that their cam 45 faces 49 coact to permit of the movement of the brake member 44 away from the drum 31 and the consequent movement of the drum 31 away from the brake member 43, as shown in Fig. 5. Preferably each of 50 these brake members 43 and 44 are provided with suitable facings 50 so as to increase their gripping effect upon the sides of the drum. The latter is herein constructed as shown so as to permit the association of the 55 brake members 43 and 44 with a central disk portion of the drum, in compact relationship within the peripheral band of the drum.

If now the shaft 20 should be reversed by the weight of the load acting through the 60 sprocket wheel 27, it will be apparent that

the parts will assume the position shown in Fig 6 wherein the brake members 43 and 44 operatively engage the drum 31 so as to be held stationary thereby, with the result that the shaft is also held stationary. 70 Also it will be apparent that the brake members 43 and 44 constitute in effect a friction clutch operating to produce a gradually effective connection between the brake drum and the shaft. 75

Upon the forward end of the shaft 20 there is mounted a sleeve 51 held against forward endwise movement by means of a nut 52 screw-threaded on the shaft, and a second sleeve 53 is journaled upon the shaft 80 inwardly of the sleeve 51 and has rigid with its inner end a brake disk 54 adapted for frictional engagement with the face of a disk 55 constituting the hub of the sprocket wheel 27 which is keyed to the shaft. Complementary cam faces 56, similar to the cam faces 49 above referred to, are provided upon the adjacent end of the sleeves 51 and 53, and the arrangement is such that when the sleeve 51 is rotated through the operation of the crank 30, the cam faces permit of the inward movement of the brake disk 54 toward the brake member 55 and hence into non-rotative relation thereto. 90 Thus movement is imparted to the sprocket wheel 27 and through its associated connections to the winding drum 16. In this rotation of the shaft 20, the brake members 43 and 44 are released from the drum 31, as 95 above set forth, so that the shaft 20 is left 100 free to rotate. The disk 54 preferably has a facing 50^a.

The brake disk 54 preferably is provided upon its periphery with ratchet teeth 57 adapted to be engaged by a pawl 58 (Fig. 4) which is suitably mounted in the framework 17. If now the sprocket wheel 27 should be rotated reversely by the action of gravity upon the load carried by the platform 14, it will be apparent that the pawl 105 58 engaging with the ratchet teeth 57 will hold the latter stationary, and the shaft 20 in such rotation will cause the sleeve 51 to rotate reversely until the cam faces 56 are moved into the relationship shown in Fig. 110 5. In this position of the parts, it will be observed, the brake disk 54 is permitted to move away from the brake member 55, and in such reverse operation of the shaft 20 the brake members 43 and 44 are caused to 115 engage the drum 31 and lock the shaft against rotation and hence the platform against downward movement as hereinbefore set forth.

It will thus be seen that the shaft 20 may 120 be rotated either by motive power supplied by an electric motor and its operating connections, or by hand power supplied through the crank 30; and that irrespective of whether the one form of power or the other 125 130

is employed, the brake mechanism functions the same in each case, viz, to permit of the rotation of the shaft to lift the load, but operatively to engage the brake drum immediately upon the reversal of rotation of the shaft by the operation of gravity whereby to sustain the load in the desired elevated position. When it is desired to permit the load to descend, this may of course be accomplished through the operation of the brake release lever 33.

When the shaft 20 is rotated through the operation of the sprocket 27 by motive power, the crank 30 remains stationary by reason of the movement of the brake disk 54 away from the brake member 55, as permitted by the cam faces 56. Thus the danger of damage to the operator by reason of a constantly rotating crank is eliminated. On the other hand, when the shaft 20 is rotated by the manual means, the sprocket 27 is also rotated so that means is provided for disconnecting the sprocket from the motor. This means may comprise a suitable clutch 59 interposed in the countershaft 21 and operable by means of a hand lever 60 through the medium of a collar 62 in the usual way, the lever being fulcrumed upon a bracket 61.

The clutch 59 is also adapted to be operated automatically when the platform attains a predetermined height so as to disconnect the motive power actuating means from the motor. For this purpose, I have provided the lever 60 with a rigid rearwardly extending arm 63 (Fig. 1) which is connected with the platform by means of a chain 64. The parts are so arranged that when the platform attains the predetermined height, the chain becomes taut and actuates the lever 60 to throw out the clutch. The chain is herein shown as extending upwardly from the arm 63 a short distance over a cross bar (not shown) of the frame 13, by which it is partially supported when the platform is near the lower end of its movement.

It will be seen that I have produced a tiering machine which is of a very practical character. The construction is relatively simple and while capable of operation either manually or by motive power is extremely efficient in character.

I claim as my invention:

1. An elevating apparatus comprising, in combination, a platform guided for up and down movements, a winding drum with which said platform is operatively connected, and means for rotating said drum to elevate the platform comprising a main shaft, a countershaft, means for applying motive power through the countershaft to said main shaft, and means for applying manual power to the main shaft adapted to remain inoperative during the operation of

the shaft by a motive power means, said motive and manual power means being operable independently of each other.

2. An elevating apparatus comprising, in combination, a platform guided for up and down movements, a winding drum with which said platform is operatively connected, and means for rotating said drum to elevate the platform comprising a main shaft, a countershaft, means for applying motive power through the countershaft to said main shaft, means for applying manual power to the main shaft, said motive and manual power means being operable independently of each other, and brake mechanism associated with said main shaft and including a brake drum, a brake band, and friction means operable automatically to lock the drum to its shaft and hold it against reverse rotation irrespective of the power means employed to rotate it.

3. An elevating apparatus comprising, in combination with a platform mounted for up and down movements, means for causing the platform to move upwardly including a main or driven shaft, and a brake mechanism including a brake drum, a brake band, cam means normally operating to cause the band to engage the drum whereby to hold said shaft against reverse rotation, and cam means acting automatically in the rotation of said shaft in a direction to raise the load to release the shaft.

4. An elevating apparatus comprising, in combination with a platform mounted for up and down movements, means for causing the platform to move upwardly including a main or driven shaft, and brake mechanism normally operable to hold said shaft against reverse rotation but acting automatically in the rotation of said shaft in a direction to raise the load to release it from the brake mechanism.

5. An elevating apparatus comprising, in combination, a main or driven shaft, means actuated in the rotation of said shaft to elevate the load, means for rotating said shaft including a motor, a countershaft operatively connected with said motor and said main shaft, brake mechanism associated with said main shaft and operable automatically to release said shaft to permit its rotation in the direction to raise the load but preventing reverse rotation, and a clutch interposed in the connection between said motor and said main shaft.

6. In an elevating apparatus, the combination of means for raising a load comprising a main shaft, brake mechanism normally acting to hold said shaft against rotation so as to permit the descent of the load, and means operable automatically when said shaft is rotated in a direction to raise the load to render said brake mechanism inoperative.

7. An elevating apparatus comprising in

- combination with a platform, an upright frame in which said platform is guided for up and down movements, a winding drum operatively connected with said platform,
- 5 means for rotating said winding drum in a direction to raise the platform including a main or driven shaft, a countershaft, a motor, means operatively connecting said countershaft with said main shaft and with
- 10 said motor, the last mentioned means including a clutch, and brake mechanism operatively associated with said main shaft and operable automatically to release said shaft to permit of the elevation of the load but
- 15 prevent reverse rotation whereby to check the descent of the load.

8. An elevating apparatus comprising, in combination with a platform, an upright frame in which said platform is guided for
- 20 up and down movements, a winding drum operatively connected with said platform, means for rotating said winding drum in a direction to raise the platform including a main or driven shaft, a countershaft, a
- 25 motor, means operatively connecting said countershaft with said main shaft and with said motor, the last mentioned means including a clutch, manual means adapted to remain stationary in the rotation of the shaft
- 30 by the motor but operable to rotate said main shaft at will and brake mechanism operatively associated with said main shaft and operable automatically to release said shaft to permit of the elevation of the load but preventing reverse rotation of the shaft whereby to check the descent of the load.

9. An elevating apparatus comprising, in combination, a load-supporting platform mounted for up and down movements, means
- 40 for elevating said platform including a main or driven shaft, means for applying motive power to said shaft to rotate it in the direction to raise the load, independent means inoperative during the rotation of the shaft
- 45 by motive power for rotating said shaft manually in the same direction, and a clutch interposed between said shaft and the source of motive power adapted to permit of the rotation of the shaft by hand power.

- 50 10. In an elevating apparatus the combination of a main or driven shaft, means operatively connected with a source of motive power to rotate said shaft in one direction, and means for rotating said shaft manually
- 55 in the same direction including cam means operable by said manual means to effect a connection between the manual means and said shaft.

11. In an elevating apparatus the combination of a main or driven shaft, two separate means for imparting rotation to said shaft in one direction, one of said means having a permanent connection, with said shaft, and the other of said means being adapted
- 60 normally to permit of the actuation of

the said shaft by the first means, and also operable upon the application of power thereto to effect operative connection between it and the shaft.

12. In an elevating apparatus the combination of a shaft to be driven, two separate means for imparting rotation to said shaft one of said means having a permanent connection with the shaft, and the other one of said means having an operative connection with the shaft effective when power is applied thereto, and brake mechanism normally acting to permit of the rotation of said shaft in one direction but to hold the shaft against reverse rotation.

80 13. In an elevating apparatus the combination of a shaft to be driven, two separate means for imparting rotation to said shaft one of said means having a permanent connection with the shaft, and the other one of said means having an operative connection with the shaft effective when power is applied thereto, and brake mechanism normally acting to permit of the rotation of said shaft in one direction but to hold the shaft against reverse rotation, said brake mechanism comprising cam means operable upon the shaft as it rotates in one direction to effect the release of the shaft from the brake mechanism but operable upon a reverse rotation of said shaft to again render the brake mechanism effective.

85 14. In an elevating apparatus the combination of a main or driven shaft, means for rotating said shaft, and brake mechanism operatively associated with said shaft and adapted normally to permit of the rotation of said shaft in one direction but acting upon reverse rotation of the shaft to re-engage it, said means comprising a pair of cam members, and a pair of brake members operable by said cam members toward or away from each other depending upon the direction of rotation of said shaft.

90 15. In an elevating apparatus the combination of a main or driven shaft, a brake mechanism operatively associated with said shaft and comprising a drum journaled upon the shaft, a brake member movable toward and away from said drum, and cam means comprising a cam sleeve fixed to said shaft and a cam member rigid with said brake member, said cam means being operable to effect a movement of the brake member toward or from the drum depending upon the direction of rotation of said shaft.

95 16. In an elevating apparatus the combination of a shaft to be driven, a member fixed to said shaft and operatively connected with a source of motive power, a pair of cam sleeves mounted on said shaft so as to rotate with reference thereto, a member carried by one of said sleeves and adapted to move toward or from said fixed member,

- 5 said sleeves having coacting cam faces adapted upon the rotation of said fixed member by motive power to effect the movement of said movable member away from the fixed member, and manual means for rotating one of said sleeves.
- 10 17. In an elevating apparatus the combination of a shaft to be driven, two separate and independent means for rotating said shaft in one direction, and brake mechanism operable to permit the rotation of said shaft in said direction but adapted to check reverse rotation, said brake mechanism comprising a movable brake member and cam means for effecting the movement of said brake member in one direction or the other depending upon the direction of rotation of said shaft.
- 15 18. In a machine of the character described the combination of a shaft to be driven, means for rotating said shaft in one direction, and brake mechanism operable to permit such rotation to act to check reverse rotation, said brake mechanism comprising a disk journaled on the shaft, a pair of brake members upon opposite sides of said disk, and means for effecting relative movement between said disk and said members either into or out of operative engagement depending upon the direction of rotation of said shaft.
- 20 19. In a machine of the character described the combination of a shaft to be driven, means for rotating said shaft in one direction, and brake mechanism operable to permit such rotation to act to check reverse rotation, said brake mechanism comprising a disk journaled on the shaft, a pair of brake members upon opposite sides of said disk, and means for effecting relative movement between said disk and said members either into or out of operative engagement depending upon the direction of rotation of said shaft and comprising a pair of cam members one of which is rigid with one of said brake members and the other of which is fixed to said shaft, said cam members having complementary cam faces operable upon the rotation of the shaft to effect such relative movement between the brake members and said disk.
- 25 20. In an elevating apparatus the combination of a driven shaft and two separate means for rotating said shaft, one of said means including a disk rotatable on the shaft, cam means operable upon the rotation of said shaft in one direction by one of said means to effect a connection between said disk and said shaft and means to permit the rotation of said disk in one direction but preventing its rotation in the opposite direction whereby to render said actuating means inoperative.
- 30 21. In an elevating apparatus the combination of a driven shaft and two separate means for rotating said shaft, one of said means including a disk rotatable on the shaft, and cam means operable upon the rotation of said shaft in one direction by one of said means to effect a connection between said disk and said shaft.
- 35 22. In an apparatus of the character described the combination of a shaft to be driven, a member fixed upon said shaft, a second member movable toward and away from the fixed member, a third member adapted to receive power for rotating the shaft, said second and third members having cam means therebetween whereby upon the rotation of the third member the second member is moved into operative engagement with the fixed member, and means for retaining said second member against reverse rotation whereby to effect its movement away from said fixed member upon the reverse rotation of the shaft.
- 40 23. In an apparatus of the character described the combination of a shaft to be driven, a member fixed upon said shaft, a second member movable toward and away from the fixed member, and a third member adapted to receive power for rotating the shaft, two of said members having cam means therebetween whereby upon the rotation of the third member the second member is moved into operative engagement with the fixed member.
- 45 24. An elevating apparatus comprising in combination, a shaft to be driven, a member fixed upon said shaft, a disk having a sleeve and journaled on said shaft, and a second sleeve mounted on said shaft and adapted to be rotated, said sleeves having cam faces adapted upon the rotation of said second sleeve to effect the movement of said disk into operative engagement with said fixed member whereby to effect a connection between said second disk and the shaft.
- 50 25. An elevating apparatus comprising in combination, a shaft to be driven, a member fixed upon said shaft, a disk having a sleeve and journaled on said shaft, a second sleeve mounted on said shaft and adapted to be rotated, said sleeves having cam faces adapted upon the rotation of said second sleeve to effect the movement of said disk into operative engagement with said fixed member whereby to effect a connection between said second disk and the shaft, and means for holding said disk against reverse rotation whereby to effect its movement away from said fixed member.
- 55 26. In an apparatus of the character described the combination of a shaft to be driven, means for rotating said shaft in one direction, and brake mechanism operable automatically to release said shaft whereby to permit such rotation but acting to prevent reverse rotation, said mechanism comprising a drum, a band normally operatively engag-

- ing the drum, and means manually operable to release said band from the drum.
27. In an elevating apparatus, the combination of a driven shaft and means for 5 rotating said shaft including a member rotatable on the shaft, and cam means operable upon the rotation of said shaft in one direction to effect a connection between said member and said shaft.
- 10 28. In an elevating apparatus, the combination of a driven shaft, a member rotatable on the shaft, a second member fixed on the shaft, and means operating automatically in the rotation of said shaft in one 15 direction to effect a connection between said members.
29. In an elevating apparatus, the combination of a driven shaft, means for operating said shaft by the application of power 20 including a member having a positive connection with the shaft, and mechanism for preventing reverse rotation of the shaft including a brake, and means in the nature of a friction clutch operable to produce a gradually effective connection between the brake 25 and said shaft.
30. In an elevating apparatus, the com-
- bination of a load-carrying platform mounted for up and down movement, means for raising the platform including a motor and 30 a shaft driven by said motor, and brake mechanism adapted to permit rotation of the shaft in a direction to raise the platform but including friction means for locking the shaft to the brake mechanism whereby to 35 prevent retrograde movement of the platform.
31. In an elevating apparatus, the combination of a shaft, a member loose on the shaft, a member fixed upon the shaft, and 40 means operable automatically in a relative rotation between the shaft and said member to effect a connection between said member and said shaft.
32. In an elevating apparatus, the combination of a shaft, a member loose on the shaft, a member fixed upon the shaft, and cam means operable in a relative rotation 45 between the shaft and said member to effect a connection between said member and said shaft.
- In testimony whereof, I have hereunto set my hand.

WILFRED S. YOUNG.
